(57) **CLAIM**

The ornamental design for a display screen with icon or packaging with surface ornamentation, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a first embodiment of a display screen with icon or packaging with surface ornamentation; FIG. 2 is a front view of a second embodiment of a display screen with icon or packaging with surface ornamentation; and,

FIG. 3 is a front view of a third embodiment of a display screen with icon or packaging with surface ornamentation. The broken lines are included for the purpose of illustrating environmental structure and form no part of the claimed design. Further, the design may be applied to any planar surface of a package for a consumer product. FIGS. 1-3 are provided in color.
